UNITED STATES PATENT OFFICE.

MABEL S. RICE-WRAY, OF DETROIT, MICHIGAN.

GAME APPARATUS.

1,201,100.

Specification of Letters Patent. Patented Oct. 10, 1916.

Application filed January 12, 1916. Serial No. 71,632.

To all whom it may concern:

Be it known that I, MABEL S. RICE-WRAY, a citizen of the United States of America, residing at Detroit, in the county of Wayne

5 and State of Michigan, have invented certain new and useful Improvements in Game Apparatus, of which the following is a specification, reference being had therein to the accompanying drawings.

10 This invention relates to a game apparatus and may be styled "synonym golf" as the underlying principle of the ordinary outdoor game of golf is embodied in my game apparatus, together with certain educational features which lend novelty to the game apparatus and exercise the mental faculties of participants of the game.

15 An object of my invention is to provide a simple, durable and inexpensive game of the above type which will test the skill of players, amuse juveniles, and increase or invigorate the mentality of a player as to synonymous words, thereby bringing together different lines of diversion or amusement conducive to an interesting game.

20 The construction of the game apparatus, its appurtenant parts, rules and other matters relating thereto will be hereinafter specifically described and then claimed, and 25 reference will now be had to the drawings, wherein—

Figure 1 is a plan of the game apparatus; Fig. 2 is a cross sectional view of the same, taken on the line II—II of Fig. 1, showing 30 the lid or cover of the apparatus in position; Fig. 3 is a longitudinal sectional view of the apparatus taken on the line III—III of Fig. 1; Fig. 4 is a plan of one set of cards used in connection with the apparatus 35 showing the faces thereof; Fig. 5 illustrates in plan the rear faces of a few of the cards shown in Fig. 4; Fig. 6 is a plan of a series of one of the cards shown in Fig. 4, and Fig. 7 is an elevation of a pawn of which 40 there is a series forming part of the game apparatus.

The apparatus comprises a board, plat or table piece 1, that is rectangular in plan and provided with side walls 2 and end walls 3 45 and 4, thereby providing an inclosure having the formation of a flat box or casing which can be conveniently closed by a lid or cover 5. In the box, on the bottom thereof, are longitudinally disposed parallel field pieces 6 providing alleys 7 at the side walls 2 and wells 8 between said field

pieces, said wells being defined by transverse spacing members 9 at the end walls 3 and intermediate the ends of the field pieces. 60

Each field piece has a longitudinal division line 10 and transverse spacing lines 11 providing spaces 12, in two rows extending from one end of the field piece to the opposite end thereof. Certain of these 65 spaces 12 are cut away to provide rectangular holes or pockets 13 and the bottom of each hole is formed or closed by the bottom of the box. The holes 13 are of less length than the spaces 12 thereby providing clearance at either end of a hole for a number, whereby the holes may be consecutively numbered by starting at one end of the field piece and returning to the same end after traversing both columns of spaces. As 70

clearly shown in Fig. 1 there are fifteen holes and in the spaces adjacent the holes there are printed or otherwise marked sentences or verses each containing a word having one or more synonyms. In the hole is 75 printed or otherwise marked the particular word of the sentence or verse having one or more synonyms and these sentences or verses are appropriated from well known literature and are instructive in themselves. 80

Each field piece has a "home" space 14, so designated, at the foot of the column of spaces containing the last or fifteenth hole of the field. The field pieces are identical in construction but are arranged the reverse 85 of each other whereby participants of the game sit at each end of the apparatus and easily observe matter on the field pieces. It is to be noted that the sentences or verses used in connection with one field piece are 90 different from the sentences or verses of the other field piece, consequently a greater number of prominent words and synonyms. 95

An end of each of the alleys 7 is provided with spaces 15 defined by division lines 16 and said spaces are numerically numbered. At the opposite end of each alley is a defined space 17 for a counter-pawn 18, preferably in the form of a ring or annulus made of wood and adapted to 100 be projected or shot along the alley to rest in one of the spaces 15 by reaching said space direct or by rebounding from the end wall of the alley. 105

When the game apparatus is intended for 110 two players, it has two sets of cards, a third of a set being shown in Fig. 4. There

are three cards for each of the holes 13 of each field piece, consequently there are forty-five cards and each third of the set have the back faces consecutively numbered as 5 shown in Fig. 5, to correspond to the numbering of the holes 13. The cards are designated 19 and the front face of each card is printed or otherwise marked to display a word and the definition or synonym of 10 the word. The word on each card is a synonym of the word in the hole of the field piece where the cards belong and in order that this may be accurately determined it is only necessary to refer to the back face of 15 the card to observe if the number on the back of the card corresponds to the number of the hole. For instance, consider the fifteenth hole and the sentence associated therewith reading, "We should never withhold 20 reparation when we know we are wrong." Referring now to Fig. 4 it will be observed that the fifteenth card, (lowermost card) contains a synonym of the word "reparation" and the fifteenth card containing the 25 word "restitution" can be readily placed in the fifteenth hole and the sentence completed by this particular synonym of "reparation."

A game apparatus intended for more 30 than two players may include numerous sets of cards.

Besides the counterpawns 18, there are player-pawns 20, one for each participant 35 of the game, and these player-pawns are preferably in the form of miniature golf players and of such size as to be conveniently moved from one space to another on the field pieces. These player-pawns, as well as the set of cards will be distinguished 40 by color, the player-pawns and cards of one player differing in color from the player-pawns and cards of another player. The wells 8 may also be colored to identify sets of cards therewith, and as shown in Fig. 1, 45 sets of cards are placed in each well, face up, whereby the cards can be easily read.

Assuming that two persons are to participate in a game, one of the players shoots or projects a counterpawn in the alley and 50 assuming that the counter-pawn comes to rest in number five space of the alley, then the player places a player-pawn on the fifth space toward hole number one. This constitutes the move of one player and the opponent now has a chance for hole number 55 one of his or her field. Should the opponent be successful in placing the counter-pawn in the space numbered seven of his or her alley, it is then necessary for opponent to 60 read the sentence or verse associated with hole number one, and having done so, it is next necessary for the opponent to select a synonym card from opponent's well and place the same in hole number one. The 65 first player now has a chance to reach hole

number one of his or her field if successful in shooting the counter-pawn on to the space numbered two of his or her alley, thus advancing the player-pawn to hole number one and the player must read the 70 sentence or verse aloud and place a synonym card therein. Such moves or plays, as indicated above, are continued by the players until each of the fifteen holes receives a card and the player-pawn reaches the home 75 space, thus indicating that one player has won the game.

In making the plays or moves the following or similar rules are enforced: First, should the counter-pawn come to rest on a numbered space larger than required for a move, the player loses his or her turn until the next play. Second, should the counter-pawn come to rest leaning against the walls of the alley, the player loses his 85 or her turn. Third, a straight shot or rebound of the counter-pawn counts providing it does not rest exactly half in one space and half in another. Should the counter-pawn come to rest more in one space 90 than the other, it counts in accordance with the space into which the greater part projects, and should the counter-pawn rest exactly on a division line with one half in one space and one-half in another, the player 95 may take his or her turn over. Fourth, should a player neglect to read the sentence or verse at each hole, when reaching the same, the player forfeits his or her right to another turn. Fifth, each player having 100 successfully reached a hole, correctly placed a synonym card therein, is entitled to another turn. Sixth, an opponent may examine the cards of a player placed in the holes to determine if proper synonyms have 105 been selected. This may be checked by comparing numbers on the back of the cards with the numbers at the holes. Seventh should a player place a wrong synonym card in a hole, the player must start over again, 110 and if having passed a number of holes, the cards are removed therefrom and placed in the well. Eighth, each player takes his or her turn in regular order, first on one side and then on the other and after a game has 115 been won, adversaries change sides or switch the game board around so that the participants at a game may have a chance at both golf fields. Ninth, should a player be privileged to move a greater number of 120 spaces than exists between two holes, then the player-pawn is advanced such spaces providing the player reads the sentence or verse aloud and selects a proper synonym card for the hole. Tenth, four or six persons can play, choosing partners for opposite sides, the partners using individual player-pawns and the synonym cards of their well.

From the foregoing it will be observed 130

that a game apparatus as defined above provides a very interesting game and the rules or regulations governing the same may be varied in many instances, according to the 5 age of the participants. For instance, for juveniles numbers alone may be used for placing cards in their proper hole, whereas with adults it is essential that the sentences or verses be read and proper synonyms used 10 in order to incorporate the educational feature in the game.

The game board may be constructed of 15 strong and durable cardboard and of such size as may be conveniently held upon the lap of participants in a game. With the game apparatus in the form of a box, as shown in Fig. 2, the lid or cover prevents the cards and pawns from becoming accidentally displaced, and directions may be 20 printed in the wells of the board or upon the lid or cover.

One embodiment of my invention has been illustrated and described, but it is to be understood that the structural elements are 25 susceptible to such modifications and variations as fall within the scope of the appended claims.

What I claim is:—

1. A game apparatus comprising a board 30 provided with separate alleys, wells, and sets of holes, cards adapted to be placed in the holes of said board, player pawns adapted to be moved from one hole to another, and counter-pawns movable in said alleys 35 adapted to govern the placing of said cards in the board holes and the movement of said player-pawns.

2. A game apparatus comprising a board 40 provided with sets of spaced holes, cards adapted to be placed in the board holes, player-pawns adapted to be moved from one hole to another, and counter-pawns adapted to govern the placing of cards in the board 45 holes and the movements of the player-pawns.

3. A game apparatus comprising a board 50 provided with sets of spaced holes, player-pawns adapted to be moved between the holes of said board, cards adapted to be placed in the holes of said board, and chance devices adapted to govern the placing of cards in the board holes and the movement of player-pawns between the holes of said board.

55 4. A game apparatus comprising a board having field pieces provided with spaced consecutively numbered holes, said board

having wells between said field pieces and alleys at the outer edges thereof, consecutively numbered cards adapted to be held in 60 the wells of said board and transferred to the holes of said field pieces, player-pawns adapted to be moved between the holes of 65 said field pieces, and chance devices movable in said alleys adapted to govern the placing of said cards and the movement of said pawn pieces.

5. A game apparatus comprising a board 70 provided with sets of holes, indicia about each hole including a word having a synonym, sets of cards having words thereon as synonyms of words associated with the indicia of said holes, and chance devices adapted to govern the placing of said cards in the holes of said board. 75

6. A game apparatus comprising a board 80 having sets of holes consecutively numbered, indicia about each hole including a word in each hole capable of having a synonym, sets of cards consecutively numbered on one face 85 and having the opposite faces thereof provided with words as synonyms of the words in the holes of said board, player-pawns adapted to be moved between said board holes, and chance devices adapted to govern 90 the placing of said cards and the movement of said player-pawns.

7. A game apparatus comprising a box, 95 field pieces therein provided with holes, said box having alleys and wells therein, indicia about each hole including a word in each hole capable of having a synonym, sets of cards in the wells of said box having words thereon as synonyms of the words in the holes of said field pieces, player-pawns adapted to be moved over said field pieces, and counter-pawns adapted to be moved in the alleys of said box and govern the placing of said cards and the movement of said 100 player-pawns.

8. A game apparatus having indicia including words of which there are synonyms, cards having thereon words as synonyms of the first mentioned words and adapted to be placed over said words, and a chance device adapted to govern the placing of said cards in connection with said indicia. 105

In testimony whereof I affix my signature in presence of two witnesses.

MABEL S. RICE-WRAY.
